UNITED STATES PATENT OFFICE

KARL SCHULTE, OF DUISBURG-RUHRORT, GERMANY

ROLLER CONVEYER

Original application filed May 4, 1925, Serial No. 27,983, and in Germany December 10, 1924. Divided and this application filed October 30, 1928. Serial No. 316,069.

This invention relates to roller conveyers as described in the U. S. Patent 1,725,740, of which this application is a division.

In cases where a conveyer roller is to be used, the diameter of which is smaller than can be afforded by the construction of the roller unit according to Fig. 3 of the application No. 27,983 with outside rotor or where the material to be conveyed is to be drawn off at the end of the transport-way in one direction only, it is advantageous, to lengthen the rotor which turns on a fixed shaft in the interior of the stator and to form this extension as a conveyer roller.

15 In the drawing Fig. 1 is equal to Fig. 2 of the application Nr. 27,983 and shows a longitudinal section of the object of the invention. Fig. 2 is a plan view of a roller conveyer with several rollers lying side by side. Fig. 3 shows a part of the roller conveyer in side view.

The nonturning shaft 1 is supported in the two side beams 2, which rest on the common plate 3. On the shaft 1 turns in bearings 4 25 the roller 5, which forms at its end 5^a the rotor of a short-circuit-electromotor. This part 5^a of the roller is surrounded by the stator 6, which is fastened on the plate 3. In the stator 6 are fastened the magnet-systems 7, to 30 which the electric current is led by the conductors 8. The stator 6 and the part 5^a of the roller working as a rotor are protected against dirt and damage by the plate 9.

In Figs. 2 and 3 is clearly shown, how the 35 material 10 is conveyed by the rollers 5.

What I claim is:

A roller unit in a conveyer of the type described, comprising a support, a stationary shaft resting on said support, an electric motor having its rotor element rotatably mounted on said shaft, and a stator surrounding a portion of said rotor, and means supporting said stator on said support.

40 In testimony whereof I have signed my 45 name to this specification.

KARL SCHULTE.
